(57) **CLAIM**

The ornamental design for a cleaning kit, as shown and described.

DESCRIPTION

FIG. 1 is a perspective view of a cleaning kit showing my new design.

FIG. 2 is a front view of a cleaning kit.

FIG. 3 is a rear view of a cleaning kit.

FIG. 4 is a left side view of a cleaning kit.

FIG. 5 is a right side view of a cleaning kit.

FIG. 6 is a top view of a cleaning kit.

FIG. 7 is a bottom view of a cleaning kit; and,

FIG. 8 is a perspective view of a cleaning kit, shown in an open state.

The broken lines in the drawings depict portions of the cleaning kit that form no part of the claimed design.
